CLAIM

The ornamental design for a end cap for heat exchangers, as shown and described.

DESCRIPTION

FIG. 1 is an isometric view of an end cap for heat exchangers, showing my new design;

FIG. 2 is a side elevational view thereof;

FIG. 3 is an elevational view taken from the left side of FIG. 2;

FIG. 4 is an elevational view taken from the right side of FIG. 2;

FIG. 5 is a top plan view thereof;

FIG. 6 is a sectional view taken along line 6—6 of FIG. 5;

FIG. 7 is a sectional view taken along line 7—7 of FIG. 5;

FIG. 8 is a sectional view taken along line 8—8 of FIG. 5;

FIG. 9 is a bottom plan view thereof;

FIG. 10 is a side elevational view showing the end cap in place on a heat exchanger, which heat exchanger is shown in broken lines for illustrative purposes only.

FIG. 1FIG. 2FIG. 3FIG. 4FIG. 5FIG. 6FIG. 7FIG. 8

FIG. 9

FIG. 10
